ATTORNEY.

UNITED STATES PATENT OFFICE.

JULIUS OLESCHAK, OF PHILADELPHIA, PENNSYLVANIA.

LOCK.

No. 799,666.

Specification of Letters Patent.

Patented Sept. 19, 1905.

Application filed October 20, 1904. Serial No. 229,220.

To all whom it may concern:

Be it known that I, JULIUS OLESCHAK, a subject of the Emperor of Austria-Hungary, residing at Philadelphia, in the county of 5 Philadelphia and State of Pennsylvania, have invented certain new and useful Improvements in Locks, of which the following is a specification.

My invention relates to that class of locks 10 in which the bolt is operated by means of a rotary cylinder containing a series of transverse tumblers which are adapted to lock the cylinder by the engagement of the ends of the tumblers with holes in an outer cylinder 15 or casing.

The object of my invention is to improve 20 the construction and cheapen the cost of this class of locks by making each of the tumblers of a single piece of wire, which is bent or folded in the form of an inverted S.

The nature of my improvements will be 25 more fully understood by reference to the accompanying drawings, forming part of this specification, in which—

25 Figure 1 represents a perspective view of a lock embodying my improvements. Fig. 2 illustrates a vertical section taken transversely through the cylinder on a line 2 2 of Figs. 1 and 4, showing the construction and 30 arrangement of one of the tumblers. Fig. 3 shows a similar section on a line 3 3 of Figs. 1 and 4, showing the arrangement of the tumbler adjacent to that shown in Fig. 2. Fig. 4 illustrates a transverse section taken on the 35 line 4 4 of Fig. 2. Fig. 5 illustrates a detached perspective view of the cylinder, and Fig. 6 is a detached perspective view of one of the tumblers and spring.

Referring to the several parts of the drawings by letters, A represents the shell or casting of the lock, to which is fastened a cylinder A', provided with a series of holes or openings a' a', &c., to receive the ends of a series of tumblers.

45 A² is a disk-shaped enlargement formed at the base of the cylinder A', serving as a flange for screws a a, by which the portion A is united to the cylinder A'.

B is a rotary cylinder containing a series 50 of wire tumblers C and provided with holes B' B' to receive the projecting ends of these tumblers. The cylinder B has a detachable portion D, which after the insertion of the tumblers C is secured in place by a screw d.

The tumblers C are formed of steel wire, 55 which is cut the requisite length and then bent by suitable dies in the form of the letter S, the projecting ends C' C' of which are adapted to the holes B' B' of the cylinder B. The oppositely-disposed projections C' of the tumblers are provided with spiral springs E, which bear at one end against the bent portion of the tumbler and at the other against the inner wall of the tumbler-cylinder. The disposal of the tumblers C within the cylinder is such that when the first is pressed downward by its spring the next in order will be pressed upward, and, moreover, while the spring on the first tumbler is located at the left of the tumbler the next in order is located 70 to the right. The object of this arrangement permits the use of a key having unlike undulating sides, which practice makes the tumblers much more difficult to manipulate without the aid of a properly-fitted key than where 75 the tumblers are arranged to be operated upon from one side of the key only.

F is the bolt, which is conventionally operated by the cylinder B, and G (see Fig. 4) is 80 the key for manipulating the tumblers.

Having described my invention, what I claim, and desire to secure by Letters Patent, is—

1. A lock comprising a fixed, and a movable cylinder, a plurality of tumblers guided 85 in holes in the movable cylinder and adapted to register with corresponding openings in the fixed cylinder, each of the tumblers being formed of a strip of metal bent or folded to form two loops, one to engage a key and the 90 other a spring under tension, substantially as specified.

2. A lock comprising a fixed cylinder and a movable one, a plurality of S-shaped tumblers formed from a single strip of wire folded 95 to form oppositely-disposed ends which are guided in the movable cylinder, and springs encircling the tumblers to cause the same to move into engagement with the fixed cylinder, substantially as specified. 100

3. A lock comprising a fixed and a movable cylinder the latter being formed of two parts which are detachable for the insertion and removal of tumblers, a plurality of tumblers guided in holes in the movable cylinder, and adapted to register with corresponding openings in the fixed cylinder, said tumblers being formed from a single piece of wire 105.

bent in such a manner as to form two oppositely-disposed loops, and a spiral spring interposed between one of said loops and the inner wall of the movable cylinder, substantially as specified.

4. A tumbler for locks composed of a single strip of wire bent or folded to form oppositely-disposed loops, the parallel ends of which are adapted to be guided in the inner

or movable cylinder of a lock, substantially to in the manner shown and described.

In testimony whereof I affix my signature in presence of two witnesses.

JULIUS OLESCHAK.
